UNITED STATES PATENT OFFICE

2,278,073

PROJECTION SCREEN

Thomas Smith Harkness, London, England

Application January 20, 1939, Serial No. 251,895
In Great Britain July 25, 1938

1 Claim. (Cl. 88—24)

This invention relates to projection screens for talking motion picture reproducing systems.

In such systems it is usual to locate the sound reproducing horn or horns behind the projection screen and to provide the screen with perforations to facilitate the passage of the sound. Such screens have previously been made of textile fabric or cloth, but this material has the disadvantage that it is not incombustible. It has also been proposed to make the screens of perforated sheet metal but such screens, although being incombustible, are not so easily transported and erected as cloth screens.

One object of the present invention is to provide an improved projection screen.

Another object of the invention is to provide projection screens for talking motion picture reproducing systems which are both pliable and incombustible.

A further object of the invention is to provide an improved method for the manufacture of projection screens.

The screens are made by perforating a sheet of wire gauze of small mesh to provide for the passage of sound therethrough and then spraying the wire gauze with a surfacing composition at a pressure to fill in the meshes of the gauze but to pass through the perforations.

The predominating material of the screen, at least on the projection side thereof, may be the surfacing composition or paint, the wire gauze or the like serving merely as a carrier for this material which may completely cover the wire gauze on the projection side of the screen so as to provide a smooth projection surface. The surfacing composition is preferably of a substantially fire-proof nature and provides the required white or light-coloured picture projection surface and also imparts pliability or suppleness to the screen so that it may be stretched in position and otherwise handled in substantially the same way as a screen of textile fabric.

A convenient metal fabric to employ is 70 mesh gauze of 38 gauge soft phosphor bronze wire. This gauze is perforated and then coated with a surfacing composition or paint, which may consist of a pigment, such as barytes and zinc oxide, together with appropriate oils and solvents and a small proportion of cellulose material. Alternatively, the metal fabric may be coated with water paint or distemper to provide the picture projection surface. This material has the advantage that it can be readily washed off or otherwise removed when the screen becomes dirty, and a fresh coating applied.

The surfacing composition or paint may be sprayed onto one side of the wire gauze. The resulting screen has a smooth white surface on this side and can be bent and also stretched in position in substantially the same way as a textile fabric screen. The screen is provided with apertures in known or convenient manner, for example by means of a perforating machine, and has substantially the same surface appearance and can be handled in the same way as a textile fabric screen, but has the advantage over the latter of having the combustible textile fabric replaced by an incombustible metal fabric. The apertures may for example consist of rows of circular perforations of about $\frac{1}{8}$ inch diameter located about $\frac{1}{8}$ inch apart. As the perforations are formed in the screen before it is coated, the coating should be applied in such a way as not to fill in the perforations. It has been found that if the surfacing composition or paint is sprayed on at a pressure of 40 pounds per square inch it will not fill in the perforations.

Several sections of coated metal fabric prepared as indicated above may be joined together 25 side by side in the same way as the sections of a textile fabric screen, for example by sewing together their adjacent edges. The sections of metal fabric may also be joined by securing their adjacent edges together by means of clips or by welding or fusing these edges together. A suitable method of welding together the sections of metal fabric is disclosed in British Patent No. 350,541. This method of welding provides a smooth seamless join which is invisible from the front of the screen when the surfacing composition has been applied. The perforations may be provided in the sections of metal fabric first, then the sections may be welded together, the wire screen so formed erected in position, and finally coated in situ with the surfacing composition or paint. The screen may be stretched and hung in the same way as a textile fabric screen.

A front view of a small portion of a projection screen according to the invention is illustrated in the accompanying drawing, the surfacing composition being removed from part of the screen in order to disclose the wire gauze support. In the drawing the reference 1 designates the surfacing composition which forms the picture projection surface and the reference 2 designates the wire gauze sheet to which the surfacing composition is applied, the perforations in the screen, which extend through both the surfacing composition and the wire gauze support, being design-

nated by the reference 3. In the drawing the perforations are arranged in transverse rows, the perforations in each row being staggered or displaced in a transverse direction with respect to those in the adjacent rows. Any other symmetrical distribution of the perforations may be used, for example the perforations need not be staggered with respect to those in the adjacent rows but may be spaced an equal distance apart in both the transverse (horizontal) and vertical directions, so that any four adjacent perforations are located at the corners of a square.

Other types of metal fabric, for example knitted or woven wire fabric, may be used instead of wire gauze. The wire fabric may be made of copper

wire, for example 60 mesh gauze of 37 gauge copper wire, instead of phosphor bronze wire. Other metals or alloys which provide a relatively soft or flexible fabric may also be employed.

5 What is claimed is:

A method of fabrication of projection screens for talking motion picture reproducing systems, comprising perforating a sheet of wire gauze of small mesh to provide for the passage of sound therethrough, and then spraying the wire gauze with a surfacing composition at a pressure to fill in the meshes of the wire gauze and to pass through the perforations.
